Hays.

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENING MECHANISM.

1,300,578.

Specification of Letters Patent. Patented Apr. 15, 1919.

Application filed July 1, 1918. Serial No. 242,699.

To all whom it may concern:

Be it known that I, FRED S. CARR, a citizen of the United States, and a resident of Newton, in the county of Middlesex, Commonwealth of Massachusetts, (whose post-office address is care of Carr Fastener Company, Cambridge, Massachusetts,) have invented an Improvement in Fastening Mechanism, of which the following description, in connection with the accompanying drawings, is a specification, like characters on the drawings, representing like parts.

This invention pertains to improvements in fastening mechanism, and more particularly, though not exclusively, to fastening mechanism for securing a plurality of different elements together by studs and sockets without the use of a long stud. The invention is particularly useful in connection with the securing of automobile curtains to the body of a car, and is disclosed in this connection. While the invention is of general application, it is particularly useful in connection with stud and socket fasteners of the type adapted to be separated by tipping movement in one direction only.

In the drawings:

Figure 1 is a front elevation of a preferred form of my invention; and
30 Fig. 2 is a section on the line 2—2 of Fig. 1.

In the preferred form of my invention I have shown a stud 3 secured to the side 4 of an automobile, and having a head 5 presenting a neck 6 adapted to be engaged by any suitable jaw mechanism 7 carried in a casing 8 of a socket attached to a curtain 9. As before stated, the socket is preferably of that type which permits separation thereof from the stud 3 only by an outward pull on the socket below the axis of the stud 3. In the preferred form of socket, the casing 8 is secured at the back of the curtain 9, and a clench-plate 10 on the front of the curtain 9 forms the front of the socket.

In the preferred form of my invention, I secure a second stud 11 to the plate 10 at a point preferably above the aperture in the socket which engages the stud 3 and mount on a second curtain 12 any suitable socket 13, preferably of the same general type as heretofore described as attached to the curtain 9.

The location of the stud 11 at a relatively high point on the socket by which it is car-

ried, enables me to separate the socket 13 from the stud 11 by an outward pull on the bottom portion of the curtain 12 without exerting any substantial outward force on the bottom of the socket carried by the curtain 9. 60 I am, therefore, by my invention enabled to separate the socket 13 from its stud without danger of separating the socket carried by the curtain 9 from the stud 3. This is of marked advantage over that type of fastener 65 in which the stud 11 is mounted centrally on the front of its coöperating socket, because, where the latter construction is used, an outward pull on the bottom of the curtain 12 is very likely to separate both curtains 70 from the body of the car, while leaving the two curtains joined together.

While I have shown and described a preferred form of one embodiment of my invention, it will be understood that major 75 changes involving omission, substitution, alteration and reversal of parts, and even changes in the mode of operation, may be made without departing from the scope of my invention, which is best defined in the 80 following claims.

Claims:

1. Securing means for securing a plurality of objects together including a pair of coöperating stud and socket members, a second pair of stud and socket members, one member of one pair being permanently secured to one member of the other pair at a point out of line therewith.

2. Securing means for securing a plurality of objects together including a pair of coöperating stud and socket members, separable one from the other by tipping movement in one direction only, a second pair of stud and socket members of the same 90 character, one member of one pair being permanently secured to one member of the other pair at a point out of line therewith.

3. A fastening device for automobile curtains including a relatively short stud secured to the automobile body, a socket secured to an automobile curtain for engagement with said stud, a second relatively short stud carried by said socket at a point above the stud-engaging portion of said 105 socket, and a second socket carried by a second curtain, for engagement with said second stud.

4. A fastening device for automobile curtains including a relatively short stud se- 110

cured to the automobile body, a socket secured to an automobile curtain for engagement with said stud, a second relatively short stud carried by said socket at a point 5 above the stud-engaging portion of said socket, and a second socket carried by a second curtain, for engagement with said sec-

ond stud, said studs and sockets coöperating to provide a three-side lock separable by relative tipping of said studs and sockets in one direction only. 10

In testimony whereof, I have signed my name to this specification.

FRED S. CARR.
